UNITED STATES PATENT OFFICE.

CLARENCE CLAUDE TURNER, OF PORTLAND, OREGON, ASSIGNEE OF ONE-HALF TO
GEORGE YALE, OF PORTLAND, OREGON.

AUTOMATIC SIGNALING AND TRAIN-STOPPING DEVICE.

1,080,087.

Specification of Letters Patent. Patented Dec. 2, 1912.

Application filed May 27, 1912. Serial No. 699,946.

To all whom it may concern:

Be it known that I, CLARENCE CLAUDE TURNER, a citizen of the United States, resident of the city of Portland, county of Multnomah, State of Oregon, have invented a certain new and useful Improvement in Automatic Signaling and Train-Stopping Devices.

My invention relates to automatic signaling and stopping devices for railway vehicles and train of vehicles, equipped either with electric motors or steam, or other locomotives for propelling, and with air or electric or other automatic brakes for retarding 15 and stopping same.

The general object of my invention is to provide a safe and reliable automatic means of performing independently of the motorman or locomotive engineer some of the 20 functions he is usually expected to perform while in charge of his vehicle or train, but which he may for any of various reasons, be unable to, or neglect to perform.

Railroads equipped with trains operated 25 by steam locomotives, or as in case of inter-urban electric lines, by motor cars, usually have their roads divided into "blocks", each block being provided with signals, the purpose of these signals being to show the line 30 clear, or otherwise in the block, or section immediately ahead of the signal shown.

Should the signal ahead of a moving train show "danger" the engineer or motorman would ordinarily shut off his propelling 35 power and apply the brakes, but should he for any reason fail to do so, my invention is devised to operate automatically in combination with any electro-mechanical railway signaling system, so that part of an electric circuit connecting with a third rail is 40 closed in such a manner that when certain electro-mechanical contrivances on the moving vehicle come in contact with the aforementioned third rail, they are automatically put 45 into operation and shut off the propelling forces, apply the brakes and display and sound signals.

Figure 1 shows the electro-mechanical device carried by the vehicle, train or engine, 50 and a diagram of the wiring and relay which completes the required electric circuit to put same in operation, either in combination with an automatic block signaling system, or by an independent distant operating circuit. Fig. 2 shows a portion of the

side elevation of a locomotive with the electro-mechanical stopping device in the inoperative position. Fig. 3 is the side elevation of a portion of a locomotive with the electro-mechanical stopping device in the 60 operative position caused by the contact of the roller 2 with the third rail 1, which completes an electric circuit through same when the relays are set by a danger signal. Fig. 4 is a plan view of a part of a railroad 65 track, showing a semaphore at danger caused by a train on block relay section and how said train completes the circuit through the relay so that when the roller 2 of a train following in the rear contacts with the 70 third rail 1, this contact completes the operative circuit to stop the following train.

To describe my device more in detail, 1 is a short section of third rail laid in close proximity to and parallel with, the main 75 track rails, having its top surface several inches above the level of the surface of the main track rails, and insulated from same and from the ground. The top surface of this third rail is curved slightly downward 80 at the ends, best shown in Fig. 3, so that the roller 2, which is carried by brackets 2' on the moving vehicle, will readily ride upon said rail. The spring 3 tends to press the outer end 2" of the bracket 2' in a 85 downward direction, the object of which is to preserve a contact between the roller 2 and rail 1.

1' is a single section of main track rail, 90 insulated at each end from the rest of the track by suitable insulators 1" so that it has no conducting connections with the rest of the railway track, 4 is an insulated electric wire connecting the third rail 1 to the contact points 4' of an electric relay 6. 95

5 is an insulated electric wire connecting the insulated rail 1' with the armature 6 of the relay 6.

7 and 7' are electrical connections from the relay 6 to the ahead distant signal. 100

8 and 8' are electrical connections to the rear distant signal.

9 is a storage battery or electric generator carried on the moving vehicle or train.

9' is an electric conductor connecting one 105 terminal of the battery or generator 9 with 9" a ground through the moving vehicle.

10 is an electric conductor connecting the other terminal of the source of power 9 to various instrumentalities on the moving ve- 110

hicle, namely: pilot light 11, a volt meter 12, a danger light 13, a relay 14, a signal bell 15, and an electric motor 16.

17 is an electric conductor connecting the 5 roller 2 to one terminal of the magnetic coil of the relay 14.

17' is a conductor connecting the other terminal of the relay 14 with the conductor 10.

10 14' is the armature of the relay 14.

14'' is a split spring contact terminal on relay 14.

14''' is the magnet core of the relay 14 and 14'''' is a terminal connecting 14' with 15 the grounded conductor 9''.

18 is an electric conductor connecting 14'' with signal lamp 13, electric bell 15 and the contact point 18'.

19 is an electric conductor connecting one 20 terminal of motor 16 with contact point 19'.

20 is a revolving commutator, 20' is an insulated portion of commutator 20.

21 is a cog wheel on the armature shaft of motor 16.

25 21' is a cog wheel on shaft 21''.

22 is a worm rigidly attached to the shaft 21''.

23 is a worm wheel rigidly attached to shaft 24.

30 25 is a cog wheel rigidly connected to shaft 24.

26 is an operating wheel rigidly attached to shaft 24, having slot 26'.

25' is a partial gear wheel rigidly attached 35 to the shaft 27.

28 is an operating wheel or crank rigidly attached to the shaft 27.

28' is a connecting rod between the operating wheel 28 and the steam throttle valve 29.

40 28'' is a connecting rod from the operating wheel 28 to an electric circuit breaker 30.

28''' is a connecting rod from the operating wheel 28'''' to the whistle 31.

32 are electric conductors from circuit 45 breaker 30 to electric controller 33 and to an electric power circuit.

26'' is a connecting rod between the air brake 26' and the operating wheel 26.

34 and 34' are cog wheels rigidly attached, 50 respectively, to shafts 35 and 21''.

35' is a hand wheel rigidly attached to the shaft 35.

To explain the operation of my invention, particular reference to Fig. 1 is necessary.

55 As the train passes a section of third rail 1, the roller 2 comes in rolling or sliding contact with it, and passes over same. When the signals indicate all clear, this contact has no operative influence on the electro-mechanical device carried on the train, if how-

60 ever, by an automatic block signaling system, or any other electric or mechanical means, danger is indicated, the train is automatically stopped. This is effected by the 65 interruption of the electric current which

normally is maintained, in the ahead or rear distant signal electrical connections 7, 7', 8, 8', and which normally energizes the magnets of the relay 6, holding the armature 6' in the energized position shown on the drawing; said interruption of the electric current deenergizes the magnets of the relay 6 and releases the armatures 6', thus allowing them to spring away from the magnets and make contact with the points 4'; this contact completes an electrical connection between the third rail 1 and a rail section 1' of the main line track through the conductors 4 and 5 and armature 6' of the relay 6, said main track rail section being insulated from the rest of the track by the insulators 1''. The circuit through rail 1, conductor 4, contact 4', armature 6', conductor 5, insulated rail section 1' is completed by the grounded portion of the vehicle or train 9'', the conductor 9', the battery 9, conductor 10, conductor 17', relay coils 14, conductor 17, and contact wheel 2; when said contact wheel contacts with the third rail 1. The closing of this circuit by the contact wheel 2 touching rail 1, starts a current from the battery 9 through the circuit and energizes the relay coils 14 and magnet 14''' so that the armature 14' is drawn toward the magnets and contacts with 14'' and is held in this position by mechanical means until released. This closes motor and signal circuits, which starts the motor 16 lights red danger light 13 and rings bell 15. The current generated in the battery or generator maintains a pilot light 11, and the voltage is indicated at all times by the meter 12. When the motor circuit, etc., is automatically closed as above described, through the conductor 9', 14''', 14', 14'', conductor 18, 18', 20, 19', conductor 19, motor 16, and conductor 10 in the manner above described, current from the generator causes the motor shaft and cog wheel 21 to revolve, this wheel is in mesh with wheel 21', which is rigidly attached to the shaft 21'', this shaft is conveniently supported in suitable bearings on some convenient part of the vehicle, the worm 22 rigidly attached to the shaft 21'' engages the worm wheel 23, which is rigidly attached to the rigid or flexible shaft 24, this shaft is suitably supported in place by bearings which are attached to any convenient part of the vehicle and it is revolved by the motor the desired amount to fulfil the functions for which it is provided.

The functions of the shaft 24 are as follows:

1st: It transmits the energy developed in the motor 16 and by means of the cog wheel 25 rigidly secured to it, which by meshing with the partial gear 25', turns the shaft 27 a part of a revolution, thereby shutting off the propelling power of the vehicle or train. The propelling power may be steam or other

gas, in which case 28' pulls and closes a throttle valve 29; it may be electricity, in which case 28' would connect to 28'' and operate an electric circuit breaker 30, which would break the propelling current in the conductors 32. A similar rod 28''' may be connected to a signal whistle 31 on the moving vehicle and the disk 28.

2nd: It also transmits power from the motor 16 to air brake valve 26^a through the medium of the slotted wheel 26, which is keyed to 24, and the connecting rod 26''. The slot 26' is so arranged as to allow the pin connection of the rod 26'' to slide in it for a sufficient part of a revolution of the shaft 24 to allow the shutting off of the propelling power, by the means above described, before the pin connection of 26'' reaches the end of the slot 26', at which time the rod 26'' is pulled by the wheel 26 for a sufficient distance to operate air brake valve 26^a and so apply the brakes.

3rd: It also turns the commutator 20 which is rigidly attached to it. This commutator is devised to break the operating circuit of the motor 16 at the desired moment, which is after the respective functions above described have been performed. The commutator 20 breaks the motor circuit through the conductors 18 and 19 by the contact brush 19' coming in contact with the insulated section 20'.

To reset the automatic stopping apparatus, the operating electric circuit through the battery or generator 9 must be broken by pulling out armature 14' of relay 14, breaking contact at 14''. The mechanism can then be turned backward to its original or "set" position by means of the hand wheel 35', shaft 35 and cog wheels 34 and 34', 34 being rigidly secured to shaft 35, and 34' similarly secured to shaft 21''. These shafts being free to revolve in their respective bearings. This can also clearly be accomplished by reversing the motor.

Having described the construction and operation of my automatic signaling and train stopping device which is carried by the moving vehicle or train—which may for convenience be designated the portable apparatus—and that part of a stationary apparatus connected with the track and signaling system which directly affects said portable apparatus for which I am making a separate application, it remains to explain the action of the currents maintained in the distant signal electrical connection 7, 7', 8, 8'; when track signal shows "clear" and when track signal shows "danger."

Referring more particularly to Fig. 4, 36 is a track signal circuit battery as used with electrically operated track signals, and its function is to maintain electric currents in the regular track signal circuits. The interruption of any of these currents by any

of various causes, throws the semaphore signals affected by the particular circuit or circuits interrupted to "danger" in a manner known to those familiar with the art. It is this interruption of the signal circuit current which as hereinbefore described, releases the armature 6' of relay 6 and completes the electric conductor from the third rail 1 to the insulated section of the track rail 1' and thus sets these instrumentalities 70 so that they co-act with those on the moving vehicle to shut off the propelling power and apply the brakes.

A variety of causes put my invention into operation, a short description of some of which will plainly show its great value and utility. 1st: In a railway block signaling system equipped with my device, if a train fitted with my portable apparatus, attempts to overrun a danger signal and gets into a block which already has a train in it, or for any reason is signaled as dangerous, the train so fitted is stopped automatically in the manner hereinbefore explained. 2nd: A train despatcher may have a key so wired to a signaling system circuit that he can at will break said circuit and automatically stop a train at a particular point. 3rd: On a railway line the vehicles of which are equipped with my apparatus and wired especially for 95 same, as for instance where no other block or interlocking signaling system is in use, the battery and circuits can be arranged as shown on Fig. 4. By this arrangement, any train is protected from collision either from 100 ahead or behind, for any desired pre-arranged distance.

For instance, referring particularly to Figs. 2, 3, and 4, a train or vehicle when on a section of railroad track controlled by the track circuit battery 36 deenergizes the conductors 7, 7', of that circuit. 7, 7' of that circuit are connected to relay 6 and the latter when disengaged connects the third rail with the track section 1—so that it will stop 110 any train fitted with my portable apparatus, which may contact therewith in the manner before described.

What I claim as new and desire to secure by Letters Patent is:—

1. In a cab signaling system, a motor, a shaft driven thereby, means for shutting off the power, gearing between said means and the shaft, a member driven by said shaft, means for controlling the application of the 120 brakes, a pin and slot connection between said member and said brake controlling means permitting a predetermined movement of the shaft without operation of said brake controlling means, whereby when the motor is operated the power will first be shut off and then the brakes applied.

2. In a cab signaling system, a partial circuit on the cab including a source of energy and a magnet, said partial circuit having as 130

terminals the wheels of the vehicle and a contact device adapted to contact with stationary contacts on the roadway, a circuit and a motor therein a switch operated by said magnet adapted to close said circuit when the magnet is energized, train controlling means operated by said motor a switch in the motor circuit operated by the motor and adapted to open the motor circuit when the train controlling means have been

operated and a crank shaft connected with the motor for returning the parts to normal position.

In testimony that I claim the foregoing as my own, I affix my signature in the presence 15 of two witnesses.

CLARENCE CLAUDE TURNER.
